UNITED STATES PATENT OFFICE.

JULIUS C. RUEDT, OF MILWAUKEE, WISCONSIN, ASSIGNOR TO PHOENIX KNITTING WORKS, OF MILWAUKEE, WISCONSIN, A CORPORATION OF WISCONSIN.

KNITTING-MACHINE.

1,283,317.

Specification of Letters Patent. Patented Oct. 29, 1918.

Application filed April 22, 1916. Serial No. 92,809.

To all whom it may concern:

Be it known that I, JULIUS C. RUEDT, a citizen of the United States, residing at Milwaukee, in the county of Milwaukee and State of Wisconsin, have invented certain new and useful Improvements in Knitting-Machines, of which the following is a full, clear, concise, and exact description, reference being had to the accompanying drawings, forming a part of this specification.

My invention relates to knitting machines and is directed toward certain improvements to the ends of simplicity of construction and reliability of operation, the provision of pattern producing means in a machine of the circular type, and the provision of improved means for striping, determining the pattern, and controlling the weave.

It will be clear to those skilled in the art that the machine of my invention may be employed to knit a large variety of articles, but it will be understood that it is particularly adapted to the knitting of articles which, either finally or in the process of manufacture, are of integral tubular formation. In the production of articles of this kind, wherein a circular type machine is employed, it has been difficult, if not impossible, to provide an intermittent pattern with yarns of different colors. This has been due largely to the inherent limitations in the construction of the machine and I have eliminated the difficulty by providing an entirely novel construction which not only secures desired intermittent patterns of a simple nature, but designs of great complication as well.

In knitting machines of the circular type, operation proceeds from the rotary movement of one element relative to another, in respect to the fundamental necessity of feeding the yarn to the needles, and heretofore it has been the practice in actual machines to mount the bobbins rotatably and to mount the needles stationarily. The fact that the bobbins rotated together made the employment of any considerable number of them utterly impracticable, due to tangles of the moving strands of yarn and due to the cumbersome nature of such an arrangement. The old mechanism associated with stationary needle cylinders was necessarily such, as a matter of structure, as to leave no open way for the provision of pattern and striping mechanism and consequently the use of

these circular machines was limited to the production of plain articles of uniform texture, and while there have been offered machines for overcoming these difficulties, many of the devices offered cover structures which are either impracticable in view of the complicated nature of the same or ineffective in operation.

I mount the bobbins stationarily and rotate the needle cylinder. What I have done, however, must be distinguished from a mere reversal of parts, since this change entails and goes hand in hand with certain novel features of construction, and operation to the end of a generally improved device, and I have drawn the appended claims accordingly. By my improved construction I am enabled to employ any number of bobbins, to secure any desired striping, and I am enabled to apply pattern forming devices which not only make the combination novel but are novel in and of themselves. Relative to the striping, I provide yarn changing devices which not only make the combination novel but are novel in and of themselves. The structural features of my invention are so worked out as to admit of ready accessibility and, as to some parts, convenient interchangeability.

I shall now describe a specific embodiment of my invention by reference to the accompanying drawings, in which:

Fig. 1 is a front elevational view of the middle portion of the machine;

Fig. 2 is a front elevational view of the upper portion of the machine;

Fig. 3 is a side elevational view of that portion of the machine shown in Fig. 1;

Fig. 4 is a plan view of that portion of the machine shown in Fig. 1;

Fig. 5 is a perspective view of a portion of the operating collar which will be referred to; and

Figs. 6 to 10 inclusive are detail figures which will be explained when the parts which they illustrate are referred to.

Referring first to Figs. 1 to 4 inclusive, it will be seen that I provide a stationary table 11 supported upon suitable legs 12-12. This table carries the cylindrical housing 13 within which the vertical needle cylinder 14 is rotatably mounted, this cylinder being carried by a rotatable gear plate 15, under the table 11, which is operated in a manner to be described presently. Associated with

the vertical needle cylinder 14 is the horizontal needle dial 16, above which the housing cover plate 17 is disposed.

I have illustrated the needle mechanism only to the extent necessary in order to understand the features of my invention. So far as the needle mechanism itself is concerned, I provide nothing new, and it will therefore be understood by those skilled in the art that the yarns are fed to the needles 18-18 and to produce the tubular article illustrated at X in Fig. 3. My invention is concerned with the selection, control, and feeding of the yarns by automatic means so as to produce in the article X the proper weaves, patterns, and colorings. It is therefore unnecessary to describe with any further particularity the particular operation of the needle mechanism, and I shall therefore refrain from burdening this specification with such matter not necessarily included.

Mounted upon the table 11 are the upright posts 20-20, across which, above the needle cylinder and dial, the cross-piece 21 is secured by means of bolts 22-22. Upon this cross-piece is mounted the bobbin structure illustrated in Fig. 2. This structure comprises the main central upright post 23 which, near the bottom thereof, carries the spider 24 on each arm of which a bobbin 25 may be mounted. A pair of yarn guiding spiders 26 and 27 are provided so that the strands of yarn leading from the bobbin may be guided independently upward and then down to the feeding mechanism without interference with each other. There are two feeding devices, one on each side of the machine, as clearly shown in Fig. 4. Each of these feeding devices comprises two feeding arms 28-28 pivoted at 29 to a supporting member 30. This supporting member is also carried by the table 11. These feeding arms 28-28 are each adapted to occupy two positions, one position being that of the forward one in Fig. 3 and the other being that of the rearward one of the same figure. When the feeding part of the arm, that is the part toward the center of the machine, is in the downward position, it is in the feeding position, that is, yarn carried in the holes 31-31 is being fed to the needles. This feeding position is adjusted by means of screws 32-32 against the lower ends of which the tail members of these arms engage, as illustrated in Fig. 3. A pair of cam following rods 32^a are provided, each of said rods being associated with one of the arms 28, and the lower ends of these rods, as illustrated in Fig. 10, follow the cam surfaces 33-33 which are carried on the upper side of a ratchet wheel 34 shown in Figs. 1 and 3. In this way, as the ratchet wheel 34 is revolved, step by step, as will be described, the cam follower rods 32^a-32^a

are alternately raised and lowered so as to bring the arms 28-28 alternately into feeding position. This is accomplished by the rotation of the cams 33-33 in a manner to be described, whereby the cam follower rods 70 32^a-32^a may be subject alternately to the low cam surface *a* and the high cam surface *b*. When the cam follower rod 32^a is in engagement with the high cam surface *b* the tail portion of the arm 28 is raised, and 75 when it is in engagement with the low cam surface *a* it is lowered by the action of the spring 35 extending between the tail portion of the arm and a block 36.

Also mounted in the block 36 and another 80 guiding block 37 is a rock shaft 38 to the lower end of which a lever 39 is secured, and to the upper end of which a lever 40 is secured. A link 41 connects the lever 40 with a knife member 42 pivoted at 43 in 85 a bracket 44 secured to the top plate 17. The knife member 42 carries the blade 45. Normally this blade is held in the position shown in full lines in Fig. 3 through the action of a helical spring 46 connected between the arm 39 and the block 37. On its under side the arm 39 carries a pin 47 which is adapted to be engaged by a cam to be described. When the blade 45 is in the position shown in full lines in Fig. 3 it holds 95 the severed end of the yarn, as will be pointed out, until that strand of yarn is again placed in action.

Surrounding the table 11, as clearly shown in the drawings, is an operating collar 48, 100 upon the under side of which an annular gear 49 is disposed, this gear being a bevel gear meshing with the pinion 50 on the power shaft 51 to which power is applied in any suitable manner. This power shaft 105 51 also carries a pinion 52, this pinion meshing with the annular gear on the under side of the member 15, as has hereinbefore been pointed out.

I shall now describe the operating collar 110 by particular reference to Figs. 4, 5 and 9. Upon this collar a swinging member 53 is mounted upon a pivot pin 54, this member being of general arcuate shape. Let it be assumed, for the purposes of description, that 115 the normal position of this swinging member 53 is that shown in dotted lines in Figs. 4 and 5. This outwardly swinging movement is limited by the engagement of member 53 in the U-shaped member 55 secured 120 to the collar 48. It will be seen now that Fig. 9 is a vertical sectional view taken on a developed plane passing through the center of the pivot member 54 and through the cap screws 56-56 which secure a block 57 125 on the member 48, the purpose of this block to be described presently.

The member 53 is held in either of its two operative positions by means of a spring-pressed plunger 58 mounted in the block 57, 130

as clearly shown in Fig. 5, and adapted to engage in one or the other of the notches 59—59 in the member 53, thus latching the member 53 either in the position shown in full line or that shown in dotted line in Fig. 5.

The peripheral surface 60 of the member 53 is adapted to be engaged by one or the other of the contact arms 61—61 pivoted at 62—62 at diametrically opposite points outside the collar 48. These contact arms or members have to do with the yarn changing and since there are two yarn feeding devices with associated changing mechanism, there are two of these contact members 61—61. They are of similar construction, as are the yarn feeding and changing mechanisms and therefore it is necessary to describe only one of them and I have given the analogous parts in the two arrangements the same reference character. The manner of operation of the contact members 61—61 will now be described.

Extending downwardly from the rotating table member 15 are the arms 63—63, on one of which a cam shoe 64 is secured. A lever 65 is pivoted at 66 to a suitable part of the frame-work and is provided at its end with a cam follower 67 disposed in the circular path of the cam shoe 64. Each time that the cam shoe 64 comes around to the follower 67 it raises the follower so as to swing the lever 65 in the direction of the arrow W against the tension of the spring 68. After the follower 67 has left the cam 64, the spring 68 retracts the lever 65. At the opposite end of the lever 65 a pawl 69 is pivoted at 70. This pawl co-operates with a ratchet 71 pivoted at 72 and a stop pawl 73 also operates with this ratchet to prevent back rotation. One of the teeth of the ratchet 71 is cut deep as illustrated at 74, so that when the pawl 69 engages with that particular tooth, it is enabled to come down into operative engagement with the ratchet 73 to which a plurality of chain wheels are operatively connected on the same shaft. It will now be understood that this particular arrangement, so far as the ratchet and chain wheels are concerned, is exemplary and these parts are interchangeable so that different actions may be secured. The timing which is secured by the repeated action of the pawl 69 determines the point in the weave where the pattern comes in and, as will be pointed out, proper intervals determine the changing of the yarn and, if desired, the changing of the nature of the weave. I shall refer first to the timing chain 76 on the chain wheel 77. It will be noted that the timing chain 76 carries certain high links 78—78 at certain intervals, and these links, as they advance, are adapted to engage the roller 79 of the corresponding actuating bell crank 80 pivoted at 81. The upwardly extending arm of this

particular bell crank is connected by means of a link 82 with the contact member 61, thus, when a high link comes under the roller 79, the bell crank will be swung over to the dotted position of Fig. 4 and will swing to the contact member 61 into the position shown in dotted lines in Fig. 4. The timing chain 76 on the chain wheel 77 is the timing chain for actuating the other contact member 61, consisting in being had by way of the roller 85, bell crank 86 and connecting rod 87. It will now be seen that when the contact member 61 is thrown into its inner position, shown in dotted lines in Fig. 4, it engages the surface 60 on the member 53 and moves it from the position shown in dotted lines to that shown in full lines in Figs. 4 and 5. This member 53 carries two lugs, 88 and 89, on the inside periphery thereof, these lugs being spaced apart as shown in Figs. 4 and 5. When the member 53 is in the outer position, these lugs have no effect upon the ratchet 34, hereinbefore referred to, but when the member 53 is thrown into its inner position, these lugs engage the teeth of the ratchet 34 so as to advance the same. Thus, as the member 53 passes the ratchet 34, with the member 53 in its inner position, the ratchet 34 is twice engaged and the teeth on the ratchet 34 are such that the first engagement thereof with the cam follower rods 32—32^a onto the high cam surface b, while the second engagement then throws one of the cam follower rods onto the low cam surface a.

Thus, one of the feeding arms 28 is always in feeding position, while, for a short space of time, both of them are in feeding position.

It will now be seen that the surface 60 on the member 53 has a further function. As it comes around in its inner position, where it is thrown when the yarn is to be changed, the surface 60 engages the pin 47 on the underside of the arm 35 and swings the arm outwardly so that the knife member 42 will be made to occupy the position in Fig. 3, as shown in dotted lines, against the tension of the spring 46. When the surface 60 has passed the pin 47 the cutting mechanism is released and snaps back due to the action of the spring 46, thus severing the yarn which is being fed to the needle. It will be kept in mind that this action takes place at about the same time that the feeding arms are reversed and thus, as the feeding of one strand of yarn is completed and the yarn is cut off, the second yarn starts to feed, it being kept in mind that the second yarn starts to feed before the first yarn stops, because of the nature of the action which is secured by the cam illustrated in Fig. 10, as has been described.

It will be noted that on the table 11 I provide two stationary cam members 90 and 91, at diametrically opposite points, each of

these members having a cam surface adapted to engage the upstanding flange 92 which provides for the surface 60 on the member 53. When the member 92 contacts with either the stationary cam member 90 or 91 it is thrown outwardly into its dotted position and in this way, after the swinging member 53 has performed its function, at its inner position, it is thrown back to its outward position subject to be again affected by the action of one of the contact members 61-61.

I shall now refer to the pattern mechanism which is controlled by the timing chain 93 which is moved around in the same manner as described with reference to the timing chain 76. The timing chain 93 has the proper high links so as to engage the contact roller 94 on the bell crank 95 which, by means of a link 96, is connected with a reciprocating member 97 guided in a block 98^a, as illustrated in Fig. 4. Mounted for radial reciprocation in the operating collar 48, is a plunger block 98, held in place by friction and adapted to occupy the position illustrated in Fig. 5 or that shown in Fig. 4. In the former position, the block lies entirely within the slot in which it rides, and in the latter position it protrudes radially beyond the operating collar so as to be in position to be engaged by the reciprocating member 97. Thus, when a high link comes under the roller 94, the bell crank lever is swung around so as to move the reciprocating block 97 toward the operating collar and, the plunger block 98 then lying in its outer position, protruding beyond the periphery of the operating collar, engagement ensues and the plunger block 98 is forced inwardly. It will be seen that on the top of the plunger block 98 two lugs 99-99 are provided and when they lie in the innermost position, that shown in Fig. 5, they operate in the path of the teeth of a ratchet wheel 100 suitably mounted upon the table 11. The ratchet wheel 100 and the directly associated parts constitute the pattern mechanism, of which there are two, lying on opposite sides of the machine, as clearly shown in Fig. 1. Since they are the same in structure, I shall describe only one of them and use the same reference characters for both. The ratchet 100 turns upon a stud shaft 101 and is held in place by means of a screw 102 mounted in the bracket block 103^a. Upon the top of the ratchet 100 two cams 103-103 are formed, all of these parts being shown in full detail in Figs. 7 and 8.

Suitably mounted upon the housing member 13 in proper proximity to the ratchet 100 is a lever 104 pivoted at 105. By means of a pin 106 this lever 104 is connected with a cam 107 which is adapted to be moved upwardly and downwardly. Each of the needles 18 is provided with a lug 18^a and

the needles are adapted to rise and fall in their respective slots and to be held in any position in which they are put by means of a circular spring 18^b. Let it be assumed that the needles are in their lowermost position; it follows then that as the needle cylinders revolve the lugs 18^a will ride upon the cam 107 if that cam is in its upper position. Thus, when the cam is in its upper position it raises all the needles that pass thereby into their upper position which is the position in which they receive yarn from the feeding mechanism. On the other hand, if the cam 107 is in its lowermost position, the needles are not raised to the position in which they receive yarn. It will now be clear that when the plunger block 98 is in its innermost position the lugs 99-99 thereon will engage successively two teeth of the ratchet 100 and will move the cams carried thereby sufficiently to raise the lever 104 through the medium of a lug 108 on the lever 104. This accordingly raises the cam 107. Once in that position, the cam remains there, since the next time that the plunger block 98 comes around it is first engaged by a stationary engaging cam 109 which engages the lugs 99-99 to throw the block 98 in its outer position, so that the ratchet 100 will be unaffected until the block 98 has again been thrown inwardly by the proper action of the bell crank lever 95 which in turn is due to the next high link in the timing chain 93.

For each pattern mechanism there is provided a supporting bracket 110 in which a shaft 111 is mounted, and upon this shaft is mounted the pattern wheel 112, the periphery of which is provided with properly arranged notches 113-113 and slots 114-114. This pattern wheel in effect meshes with the needles of the needle cylinder. In other words, the lugs 18^a on the needles act as teeth which mesh with the slots or notches in the pattern wheel and revolve it.

If, however, depending upon whether a lug 18^a meshes with a notch or a slot, a different action ensues. If the lug meshes with a notch it is carried upwardly, thereby escaping its engaged loop of yarn, since it will be noted that the pattern wheel is mounted upon an inclined plane. However, if a slot is engaged there is no raising effect upon the needle, which is thus permitted to remain in its engaged loop of yarn, thereby causing the needles not raised to tuck during the knitting operation, consequently producing pattern effects upon the fabric being knitted. Let it be assumed, as before pointed out, that the needles approach the pattern wheel in their lowermost position. If a needle meshes with a slot in the pattern wheel it does its part in revolving the pattern wheel but it remains in its lowermost position. On the other hand, if the lug meshes with a

notch in the pattern wheel it not only does its part in revolving the pattern wheel but it is moved to its uppermost position. It will be clear, therefore, that by the action of the pattern wheel certain needles remain in their lowermost position while others are raised. Now, assuming that the cam 107 is in its lowermost position, it follows that the needles will occupy respectively upper and lower positions as determined by the pattern wheel. Those in the upper positions receive yarn from the yarn feeding arms 28—28 and those in the lower position are caused to tuck during the knitting operation as they remain in their engaged loop of yarn, and in this way the pattern is secured. However, when the cam 107 is in its uppermost position all the needles are forced upwardly into their upper positions regardless of what the pattern wheel may have done, and all the needles receive yarn with the result that only "plain work" is produced. It now is clear that when the cam 107 is in its lowermost position a pattern is being woven and when it is in its uppermost position "plain work" is being done. Thus, according to the action of the bell crank lever as determined by the timing chain 93, the cam 107 is made to occupy either its upper or lower position, and in this way the chain 93 determines when the pattern mechanism shall be effected and when it shall not be effected. It is assumed, of course, that after the needle has received its thread and has formed its function it moves or is moved down into its lowermost position where it will be in place for co-operation with the next pattern wheel which it approaches. It will also be clear that the distribution of the notches and slots upon the periphery of the pattern wheel may be varied so as to produce various patterns and for this reason I have made the structure so that the pattern wheels are readily replaceable. It will also be clear that the beginning and ending of the pattern may be simultaneous with the changing of the yarn so as to produce colored patterns and accordingly the timing chains are easily replaceable so as to produce the patterns at proper intervals and so as to correspondingly change the yarn colors. In this connection I also call attention to the fact that the ratchet wheels 71 and 75 are also readily replaceable so as to take part in determining the occurrence and duration of any particular condition of the machine, and in this respect I may also refer to the other ratchet wheels which may on occasion be changed or dispensed with.

A further feature to be described is that concerned with the nature of the stitch. So far as the specific mechanism for causing a plain or rib stitch is concerned, my invention is not relevant but so far as the operation of this invention is concerned, it is. Thus, on the chain wheel 77 I provide the further

timing chains 115—115 which co-operate with rollers 116 on bell crank levers 117—117. Each of these bell crank levers is connected by means of a link 118, with another bell crank 119 pivoted to the cover plate 17 at 70 120. By means of a pin 121 the free end of the bell crank 119 is operatively connected with the stitch changing mechanism lying under the cover plate 17.

When the proper high links on the chains 75 115 strike the corresponding rollers, the mechanism is actuated to change the weave from plain to rib, or vice versa, a complete mechanism being provided for each side of the machine.

It will be noted in Fig. 4 that I have provided on the chain wheel 84 other timing chains with corresponding bell crank mechanism. However, I have not shown any further mechanism connected with these extra 85 timing chains but show their presence merely to indicate the flexibility of my structure. When other special actions are required, from time to time, depending upon the particular weave under construction, I can 90 utilize other and additional timing chains, as will be evidenced.

It will now be clear that it is only the operating collar with its directly associated parts and the needle cylinder and dial with 95 their directly associated parts, which rotate and the important features, because of this fact, as pointed out at the beginning of this specification, will now be fully apparent. I may also speak of the matter of safety for 100 the operator. In view of the nature of the movable parts and the manner in which they are perfected, there is little, if any danger, of one's clothing being caught in the mechanism and no danger of physical injury where 105 handling is necessary. The nature of the means for determining the pattern makes it very simple to work any kind of design, even a very complicated one, and the machine may be readily changed to work one 110 design as distinguished from another because very few parts need be interchanged, and they are readily interchanged. Because of the inherent features of my machine, I am enabled to employ numerous colors of yarn, 115 and ample bobbins, without danger of interference between each other and without liability to disorder, since these parts are all stationary.

Changes and modifications within the 120 scope and spirit of my invention will become evident to those skilled in the art from the description herein given. I have shown and described a specific machine which I have had in practical operation and, although it 125 may be considered my preferred form, I have drawn the appended claims so as not to be limited to details which may readily be changed without departing from the mode of operation or result, but on the other hand 130

to protect as broadly as possible that which may be new. Accordingly, I have drawn claims to certain combinations regardless of the specific structure of the component elements and I have also drawn claims to specific structures of certain devices which, regardless of the combination in which they are found, are new.

I claim:

10. 1. In a knitting machine a plurality of stationary bobbins, a rotatable needle cylinder, a feeding device mounted stationarily and comprising a plurality of feeding arms, each to receive yarn from one of said bobbins and feed the same to the needles on said cylinder, means for alternately bringing said arms into and out of action, comprising a pair of vertically slidable rods for engaging the feeding arms, a ratchet having cams on its flat end face for engaging said rods, a collar concentric with and rotatable with said needle cylinder, and an arcuate arm pivotally mounted on said collar and carrying a dog for actuating said ratchet, and adapted to be moved into operative position for actuating said means.
20. 2. In a knitting machine, a plurality of stationary bobbins, a rotatable needle cylinder, needles arranged to rise in said cylinder into yarn receiving position and to fall out of such position, a pattern disk for raising selected needles, means for feeding yarn to those needles in raised position, means inactive in one position and in another effective to move all needles to raised position, an operating collar movable concentrically of the cylinder, means on said collar for controlling the position of said last named means, and means also on said collar for controlling said yarn feeding means.
30. 3. In a knitting machine, a plurality of stationary bobbins, a rotatable needle cylinder, needles arranged to rise in said cylinder into yarn receiving position and to fall out of such position, a pattern disk for raising selected needles, means for feeding yarn to those needles in raised position, means inactive in one position and in another effective to move all needles to raised position, an operating collar movable concentrically of the cylinder, means on said collar for controlling the position of said last named means, and means also on said collar for controlling said yarn feeding means.
40. 4. In combination, a table having a supporting frame, a needle cylinder having vertical needles, a rotatable operating collar, concentric with and outside of said needle cylinder, an arcuate swinging arm carried by said collar, said arm having a projection, a horizontal arm adapted to be thrown into the path of the arcuate swinging arm to change its position on the rotatable collar, a ratchet wheel having a vertical axis and having its teeth disposed in the path of the

projection on the swinging arm when the same is moved to inward position, a rotary cam wheel secured to said ratchet wheel, a pair of yarn feeding arms pivoted to feed yarn to the needles, a pair of vertical rods slidable to actuate the yarn feeding arms, said rods being adapted to engage at their lowest end said cam wheel and to engage at their upper end, said yarn feeding arms.

5. In combination, a table or frame, a vertical needle cylinder rotatable on said frame, a rotatable operating collar concentric with and outside of the needle cylinder and rotatable with said needle cylinder, an arcuate swinging arm carried by said collar, said collar having a radial projection, a pattern mechanism, a horizontal arm controlled by said pattern mechanism, said arm being adapted to be thrown in the path of the swinging arcuate arm to change its position on the rotatable collar, a ratchet wheel having a vertical axis and having its teeth disposed in the path of the projection on the swinging arm when said swinging arm is moved to its inner position, a rotary cam wheel secured to said ratchet wheel, a pair of yarn feeding arms pivoted to feed yarn to the needles, a pair of vertical rods, each adapted to engage and actuate one of the yarn feeding arms, said rods being slidable mounted and adapted to engage at their lower ends said cam wheel, a vertical projection on the swinging arcuate arm and a yarn cutting device adapted to be operated by said vertical projection.

6. In a machine of the class described a rotatable needle cylinder, a rotatable ring or collar, concentric with the needle cylinder and movable therewith, an arcuate arm pivotally mounted on said ring, said arm being adapted to be moved to an inner position and to an outer position, said arcuate arm having a radial projection and an axial projection with respect to the cylinder, pattern mechanism for moving the arcuate arm to its inner position while said ring is rotating, yarn changing means adapted to be actuated by said radial projection and yarn cutting means adapted to be operated by said vertical projection.

7. In combination, a frame, a rotatable needle cylinder, a rotatable collar concentric with and movable with said needle cylinder, an arcuate arm pivotally mounted on said ring and having a vertical flange, an arm adapted to be moved radially of the needle cylinder to engage said vertical flange and change the position of said arcuate arm on the ring, pattern mechanism for moving said last named arm, and a yarn cutting mechanism comprising a swinging arm adapted to be actuated by said vertical flange.

8. In combination, a rotatable needle cylinder, a rotatable ring outside of and rotata-

- ble with the cylinder, a swinging arcuate cam arm pivoted on the ring and having an outer and inner position, means for yieldingly holding the arcuate cam arm in either 5 position, a flange on said cam arm projecting axially with respect to the cylinder, pattern mechanism, a movable lever adapted to be swung into the path of the flange to move the cam arm into its inner position, said lever being controlled by the pattern mechanism, a projection on the cam arm and yarn changing means controlled by said projection and a yarn cutter controlled by the flange when the cam arm is in its inner position.
9. In combination, a needle cylinder rotatably mounted on a suitable frame, a concentric ring rotatable with the needle cylinder, an arcuate cam arm pivotally mounted 20 on the ring, said cam arm having an inner and an outer position, pattern mechanism for throwing the cam arm to its inner position, said cam arm having a projection extending radially toward the cylinder and having a flange extending axially of the cylinder, yarn changing mechanism adapted to be operated by the projection when the arm is in its inner position and a stationary cam adapted to engage the flange to move the 25 cam arm to its outer position.
10. In combination, a rotatable needle cylinder mounted on a suitable frame or table, a concentric ring outside of and rotatable with the needle cylinder, an arcuate cam arm pivotally mounted on said ring, said cam arm having a radial projection and an axial flange, pattern mechanism for throwing the cam arm to its inner position, yarn changing arms adapted to be operated by said radial 30 projection, a yarn cutter adapted to be operated by said axial flange when the cam arm is in the inner position and a stationary cam for throwing the cam arm to the outer position.
11. In combination, a stationary frame, a 45 rotatable needle cylinder, a ring outside the needle cylinder rotatable therewith, a pawl and ratchet mechanism, controlled by rotation of the needle cylinder, a shaft having a plurality of sprocket wheels driven in unison by said pawl and ratchet mechanism, pattern chains on said sprocket wheels comprising a stitch changing chain on one of the sprockets and a yarn changing chain on another of the sprockets, a pair of bell crank 50 levers adapted to engage said chains, a radial slide mounted on said rotatable ring, said slide having a projection at its inner end, a stitch controlling mechanism operated by said projection, a radially movable cam 55 member mounted on the frame of the table outside of the ring and being connected to one of said bell crank levers, said slide being adapted to be moved inwardly by said cam member, in position to operate the stitch controlling mechanism, an arcuate cam arm pivotally mounted on the ring, said cam arm having an axial flange and having a radial projection, said yarn changing chain 60 controlling mechanism for engaging the vertical flange to throw the arcuate arm to its inner position, and yarn changing arms adapted to be operated by the radial projection when the cam arm is moved to its inner position.
- In witness whereof, I hereunto subscribe my name this 10th day of April, A. D. 1916.
- JULIUS C. RUEDT.
